DOORSTOP

Ralph L. Johnson, Los Angeles, Calif., assignor
of one-fourth to Herbert T. Cooke, Los
Angeles, Calif.

Application December 26, 1931
Serial No. 583,216

2 Claims. (Cl. 292—139)

This invention relates to and has for an object the provision of an improved type of door stop capable of being attached to the lowermost rail of a door for engagement with the floor and to be set, as for instance, by foot pressure to provide a predetermined friction for preventing the swinging of the door, but additionally provided with means whereby an excessive pressure on the door, as by wind or otherwise, will, instead of 10 slightly moving the door, tend to more firmly lock the door against movement by increasing the friction exerted by the stop on the floor.

To this end the invention contemplates the provision of a simple, durable and economical device 15 which, as in the case of other stops, may be set and released by foot pressure, and includes a swivel stop having a friction shoe thereon for engagement with the floor which is caused to swing on its axis in one or the other direction 20 and is sensitive to the slightest movement of the door in either direction for increasing the friction and thereby preventing the opening or closing of the door when the stop is set.

Other objects may appear as the description 25 progresses.

In the accompanying drawing I have shown a preferred form of invention, in which

Fig. 1 is a top plan view of my improved door stop operatively positioned on a door.

30 Fig. 2 is a sectional elevation of the same on line 2—2 of Fig. 1.

Fig. 3 is a sectional elevation of the same on line 3—3 of Fig. 1.

35 Fig. 4 is a sectional plan of the same on line 4—4 of Fig. 2.

Fig. 5 is a perspective view of the swinging stop forming a primary part of my improvements.

Fig. 6 is a perspective view of a frictional shoe 40 adapted to be detachably supported on the stop shown in Fig. 5.

Briefly described, my invention includes a suitable casing A adapted to be firmly secured to a door D, a plunger C vertically slidable in the casing A, a stop B pivotally carried on the lower end 45 of plunger C, and a friction latch E associated with the plunger C for purposes hereinafter described.

The casing A is preferably formed of sheet metal and is provided with a body portion 1 having 50 a rectangular recess 2 formed therein and open at the top and bottom thereof. Flanges 3, 3 are bent outwardly from the opposite sides of the casing and are attached to the door D by means of screws 4, 4. An outwardly flaring skirt 55 is formed at the bottom of the casing to protect

and enclose the lower portion of the shoe B. The plunger C has a flat stem 6 of rectangular cross section and a right angularly bent upper end 7 forming a foot-piece by means of which the plunger may be depressed.

The rear edge of plunger C is cut away at 8 to clear a transverse pin 9 which extends thru and is supported in the opposite side walls 10, 10 of the casing and carries a spring F. Said spring has a central loop 11 which embraces the stem 6 65 of the plunger and engages a notch 12 in the outer edge of said plunger. The two sides of the spring are looped at 13 around corresponding portions of the pin 9 and the ends 14, 14 extend thru an opening 15 in a channeled member 16 70 forming the back of the recess 2.

The latch E is pivotally mounted intermediate the door D and the member 16 near the top of the casing on a transverse pin 17 which is carried in the member 16 and has a rectangular aperture 75 18 which embraces the stem 6 of plunger C, as shown in Fig. 2. The member E has a depending heel portion 19 which is engaged by the two ends 14, 14 of spring F. Thus spring F serves the dual purpose of tensioning plunger C and latch E. 80

The stop B is formed with a pair of similar spaced lugs 20, 20 which straddle the lower end of plunger C and are pivotally secured to said plunger by means of a transverse pin 21 held in bores 22 formed in the lugs 20. The stop B has 85 a shoe 23 which is laterally extended from the lugs 20, 20 in opposite directions and is formed with a re-entrant groove 24 longitudinally thereof, whereby a friction shoe 25 may be detachably secured to the supporting shoe 23. To this end 90 the friction shoe 25 is provided with a re-entrant rib 26 on its upper surface adapted to slide into and inter-lock with the groove 24 in the shoe 23.

The side walls 10 of casing A are bent at 27, 27 into horizontal position to form guides for the 95 plunger C, and the lugs 20, 20 of the shoe B slide between and respectively engage the inner sides of the walls 10, 10 so that the movement of plunger C is truly vertical. The outer end of member E is provided with a foot-piece 28 and the outer extremity 29 of the slot 18 in said member E is adapted to frictionally engage the outer edge 30 of plunger C so as to bind said plunger and hold the plunger at selected elevations against the tension of spring F, which tends to 105 elevate the plunger at all times.

In operation, when the device is attached to the door D the tension of spring F will automatically elevate the plunger C to its uppermost position when the latch E is depressed, permitting the free 110

movement of the plunger. Pressure on the portion 7 of said plunger, however, will lower the plunger and the friction shoe 25 into contact with the floor when and to an extent as may be desired.

5 The depression of plunger C will also correspondingly depress the plunger E against the tension of spring F and cause the latch E to frictionally engage the outer edge 30 of the plunger and to so bind the plunger that it will not of itself be restored to inoperative position.

10 It will be observed that the lower surface 31 of friction shoe 25 is but slightly arcuate, and the thrust of the shoe onto the floor is at points centrally of the shoe when the plunger is depressed. 15 Should the friction between the shoe 25 and the floor be insufficient to prevent the swinging of the door due to a sudden gust of wind or pressure accidentally applied thereto, the shoe 23 with the friction member 25 will be caused to rock on the 20 axis 21 of the shoe and a corresponding lateral portion of the shoe will engage the floor.

As shown in the drawing, the lateral edges of the shoe are at a greater distance from the axis 21 than is the central portion thereof. Therefore 25 the shoe will act as a cam for increasing the friction applied to the floor when the door tends to swing in either direction after the plunger is set to a nominally operative position.

In Fig. 2 I have shown an arc 32 which is 30 concentric with the axis 21 of the shoe for illustrating the fact that the lateral portions 33, 33 of the friction shoe 25 are of greater radius than the arc 32. For instance, if, as shown in Fig. 2, pressure is applied to the door from the right hand 35 side the shoe 23 will rock slightly on its axis 21 in a counter-clockwise direction. If on the other hand pressure is applied from the opposite side of the door the shoe will rock slightly in a clockwise direction, thus moving one or the other of the lateral portions 33 of the shoe into frictional 40 engagement with the floor, and the greater the movement of the door, the greater will be the friction applied to the floor, thus effectively preventing any but a very slight movement of the 45 door when the plunger C is operatively set.

70

75

The plunger C may be readily and quickly released from engagement with the floor by depressing the latch E and in such case the spring F is effective for elevating the plunger C and the shoe 23 to a position of complete disengagement 80 with the floor.

The skirt 5 of the casing serves to protect the shoe against accidental contact with furniture, cleaning apparatus, and the like, which might tend to break or impair the shoe or to completely 85 dislodge the friction member 25 therefrom.

What I claim is:

1. A device of the character described comprising in combination with a door, a casing attached to a side of the door adjacent the floor, a plunger 90 vertically slidable in said casing, a spring normally urging said plunger into inoperative position, a stop pivotally supported on the lower end of said plunger, a friction shoe carried on the lower end of said stop for engagement with the 95 floor, and a lock engaging said spring and said plunger means for locking said plunger and said shoe in operative position when the plunger is depressed, and for elevating said plunger when the lock is depressed.

2. A door stop comprising a casing attachable to a door and having a vertically disposed chamber therein, a plunger slidably held in said chamber, a friction shoe pivotally carried on said plunger for engagement with the floor, a spring 100 on said casing operatively connected with and for urging said plunger to inoperative position, and a latch pivotally held on the casing and provided with a portion encompassing and for binding engagement with the plunger, and a heel bearing 110 against said spring, for tensioning the latch and the plunger, whereby when the plunger is depressed the latch will lock the same in operative position and when the latch is depressed said spring will be effective for raising the plunger to 115 inoperative position.
